(57) **CLAIM**

The ornamental design for a kitchen tool with detachable head, substantially as shown and described.

DESCRIPTION

FIG. 1 is a perspective view of a kitchen tool with detachable head showing our new design;

FIG. 2 is a side elevational view thereof;

FIG. 3 is a top plan view thereof;

FIG. 4 is a bottom elevational view thereof;

FIG. 5 is a rear elevational view thereof; and,

FIG. 6 is a front elevational view thereof.

The broken lines immediately adjacent any shade lines represent the bounds of the claimed design and form no part thereof.
